(57) **CLAIM**

The ornamental design for an utility vehicle, as shown and described.

DESCRIPTION

FIG. 1 is a front side perspective side view of a utility vehicle.

FIG. 2 is a front elevation view of the utility vehicle shown in FIG. 1.

FIG. 3 is a right side view of the utility vehicle shown in FIG. 1; the left side view of the utility vehicle being identical thereto; and,

FIG. 4 is a top plan view of the utility vehicle shown in FIG. 1.

The broken lines shown in the figures are for the purpose of illustrating either the environment or portions of the utility vehicle that form no part of the claimed design.
